RADIO FREQUENCY PULSE TRANSMISSION

Robert M. Page, Washington, D. C.

Application August 6, 1938, Serial No. 223,503

20 Claims. (Cl. 250—17)

(Granted under the act of March 3, 1883, as
amended April 30, 1928; 370 O. G. 757)

1

This invention relates to a vacuum tube means for generating oscillations, and more particularly to a generator capable of producing oscillations in pulses of very short duration and high amplitude.

Among the several objects of this invention are:

To provide an oscillation generator capable of producing oscillations, for a very short interval, at a level much in excess of the rated output of the vacuum tube in the generator;

To provide an oscillation generator that will automatically and periodically produce pulses of oscillations, the duration of such pulses being very short in comparison to the interval between pulses;

To provide an oscillation generator of the type set forth that may be controlled to generate oscillations aperiodically.

In the drawing:

Fig. 1 depicts an embodiment of my invention wherein the potential applied to the anode is automatically controlled by a high resistance in series with the anode supply and a capacitance in parallel with the said resistance and the source of supply;

Fig. 2 illustrates another form of my invention;

Fig. 3 shows my invention with the capacitance above mentioned in shunt with the resistance

Fig. 4 illustrates graphically the operation of my novel generator;

Figs. 5 and 6 depict alternative connections for the parallel connected high resistance and capacitance.

While the usefulness of the present invention is not limited to any one field, it is particularly useful as a transmitter of short waves for detecting, by reflected echoes, the presence of objects such as aircraft or ships, the determination of range, the operation of altitude and ground speed indicators, etc. The distinguishing feature of the present invention is its capacity to generate and radiate radio frequency signals of extremely short duration and high amplitude. Signal pulses of less than one microsecond have thus been produced at power levels exceeding the tube ratings by a factor of 100 or more, without apparent damage to the tube after many hours of operation.

Fig. 1 depicts one embodiment of my invention that is, in some respects, conventional in that it is a self excited tuned grid oscillator having the tunable network 7 connected to grid

8 of tube 9 and coupled to the inductance 10 connected to anode 11 of tube 9. By way of example of one use, the oscillatory networks are inductively coupled to a radiating half-wave doublet antenna 12, and a resistor 13 is connected between network 7 and cathode 14 of tube 9 to function as an input impedance when a control or synchronizing voltage is impressed through leads 15 and 16, the capacitance 17 serving as a bypass for radio frequencies.

A high resistance 18 is connected in series between source 19 of anode supply and anode 11 and a capacitance 20 is connected from the anode supply lead to cathode 14, the cathode being connected to the positive terminal of source 21 of the grid bias, and to the negative terminal of source 19 by lead 22. The bias on grid 8 is such as to prevent operation of the tube until the potential of anode 11 reaches or exceeds a predetermined value. It is evident that capacitance 20 will be charged by source 19 through high resistance 18, that the potential of capacitance 20 will thus increase up to the voltage across the source 19 and that the potential applied to anode 11 will be the same as that of capacitance 20 and hence will increase at the same rate as does the potential of capacitance 20. When the potential on anode 11 is sufficient to overcome the bias on grid 8 oscillations will be initiated. As soon as the tube 9 begins to pass current the capacitance 20 will discharge through the tube and will thus undergo a decrease in potential. Source 19 is unable to maintain the oscillations through resistance 18 and hence the operation of the tube will stop when the potential of capacitance 20 has dropped to some definite value. However, the energy stored in capacitance 20 is sufficient to maintain the output of tube 9 at a level a hundred or more times greater than the rated output of the tube and this without damage to the tube owing to the very short duration of the oscillatory condition in comparison to the time required for the potential of capacitance 20 again to build up to such value that oscillations will be initiated.

It is evident that the duration of the pulses, or oscillatory condition, will be governed by the capacity of capacitance 20 and that the time between pulses will depend upon the product of the capacity of capacitance 20 multiplied by the value of resistance 18. It is also evident that there will be no radiation whatsoever from this novel generator between pulses.

It may be desirable that the generation of oscillations should be controlled in some manner or

should be synchronized with the operation of some other apparatus. This may be effected by giving the bias on grid 8 such value that the maximum potential applied to anode 11 will be insufficient to cause the tube to operate and if then a voltage be applied through leads 15 and 16 the bias on grid 8 may be changed so that the voltage on anode 11 will be sufficient to cause the tube to pass current and a pulse of oscillations will be generated as above described. The voltage applied through leads 15 and 16 may be either periodic or aperiodic under the conditions just discussed. It will be obvious to those skilled in this art that instead of applying the control voltage to the grid circuit it may equally well be applied instead to increase the voltage of anode 11 to such value that the bias on grid 8 will be overcome and the generator thereby caused to operate. Such a circuit is shown in Figure 2 where the control voltage may be delivered to the anode voltage increasing means 29.

In the circuit of Fig. 3 intermittent high amplitude pulses are generated through the connection of condenser 29 in parallel with resistance 18. On initial operation following connection of power source 19, a very high amplitude impulse is generated, the anode current being delivered to condenser 29 which thereby is charged negatively to lower the anode voltage and terminate the impulse. The initial conditions of charge are gradually restored through the flow of current from condenser 29 through resistor 18 to reestablish the minimum operative anode potential for conduction. The quiescent period is controlled by the time constant of condenser 29 and resistor 18.

Fig. 4 shows the nature of the operation of my invention in terms of variation of anode potential with time, the anode potentials being represented by ordinates and the time by abscissas. Starting out with the potential of anode 11, that is the potential of capacitance 26, at zero the anode potential follows the rising course indicated by the curve 23 until it reaches the value V_1 at which oscillations begin and then in time t , represented by line 24, the potential drops to the value V_2 at which oscillations cease. The potential immediately begins to build up and in the time T it again reaches the value V_1 and the oscillatory condition again ensues, etc. Nothing is to be inferred as to the relative values of V_1 and V_2 or of t and T , from the scale used in Fig. 4, this figure being purely illustrative in its nature. In practice, T has been 60 or more times t . Thus, while in an absolute sense the charging period T may be very short, the charging takes place slowly relatively to the discharge during period t . Conversely, the discharge is rapid relative to the charge. It is evident that the value of resistor 18 must be sufficiently great to quench oscillations when the potential has dropped to the value V_2 .

The circuit of Fig. 3 operates similarly, the cycle beginning with time t , condenser 29 charging negatively along line 24 during oscillation, and discharging through resistor 18 gradually to increase the anode potential during time T .

The circuit shown in Fig. 5, in common with Fig. 1, is provided with condenser 29 receiving current from the tube during the pulse and operating in conjunction with a tube electrode to control its potential to terminate the operating period. In Fig. 5 condenser 29 is interposed between the cathode 14 and the negative side of the power supply 19. It accumulates a charge during space current flow to raise cathode 14 to a positive voltage which is effective as a negative grid

bias to block oscillation. The charge is drained off gradually in the blocked period through resistor 18 until the tube again becomes conductive, and in this respect the circuit resembles that of Fig. 3.

In the circuit of Fig. 6 the grid space current during operation is applied to condenser 20, which, as shown in the grid-cathode circuit and operates to shift the grid potential for blocking the oscillator at the end of the pulse, and maintaining the quiescent period during discharge through parallel resistor 18.

The high value of resistance 18 employed in Figs. 5 and 6 to effect periodic pulse generation has been found to permit emission of pulse shorter by a factor of ten than any other known method. It is further apparent that by employing space current through the tube itself to control the operating period, high power levels may be obtained without damage in a simple, self-protecting circuit.

The greatly increased instantaneous output of the tube is due to the fact that the potentials of sources 19 and 21 are greater, by factors that may be as much as six or eight, than the corresponding rated operating potentials of the tube.

This operation at excess voltage has the advantage of increasing vacuum tube efficiency somewhat at all frequencies. It has the added advantage of reducing electron flight time, thus very materially increasing efficiency at frequencies approaching the upper frequency limit of the tube used. Where frequency limit is due to electron flight time, this method of operation actually raises the upper frequency limit of oscillation. For example, a certain type tube was tested in which at normal ratings the efficiency fell off to zero at 335 megacycles. In the circuit of this invention, at three times normal voltage, efficiency of 15 percent was obtained at 390 megacycles.

The invention herein described and claimed may be used and/or manufactured by or for the Government of the United States of America for governmental purposes without the payment of any royalties thereon or therefor.

I claim:

1. A method of operating an oscillation generator that includes a vacuum tube comprising the steps, executed in repeating cycles, of storing up electric energy with continuously rising voltage while holding said generator quiescent, said voltage being operatively applied to said tube, until said voltage reaches such value that oscillations begin, discharging said stored up energy through said generator to maintain oscillations until the voltage drops to such value that oscillations cease, and radiating as a signal pulse said stored energy thus oscillating, the time of storage of said energy being many times as long as the duration of oscillations and the output during oscillation being many times the rated capacity of said vacuum tube.

2. A method of operating in repeating cycles an oscillation generator that includes a vacuum tube, comprising the steps of biasing said tube beyond cutoff, storing up electric energy with continuously rising voltage while holding said generator quiescent, said voltage being operatively applied to said tube and reaching a maximum value that is insufficient to overcome said bias, applying to said tube an additional voltage to overcome said bias and initiate oscillations, discharging said stored up energy through said generator to maintain oscillations until the total

applied voltage drops to a value such that oscillations cease, and radiating as a signal pulse said stored energy thus oscillating, the time of storage of said energy being many times as long as the duration of oscillations and the output during oscillation being many times the rated capacity of said tube.

3. An oscillation generator, comprising a vacuum tube having a cathode, a grid and an anode, oscillatory circuits operatively associating said grid and said anode, means to bias said grid to prevent operation of said tube until the potential on said anode reaches a predetermined minimum value, a source of potential difference between said cathode and said anode, a high resistance in series between said source and said anode, a capacitance of a value adequate to store a quantity of energy at said minimum potential sufficient, when radiated as a pulse, to produce a substantially powerful signal, said capacitance being connected in parallel with said source and said resistance, whereby said capacitance is slowly charged through said resistance until said minimum value of potential on said anode is reached and the energy stored in said capacitance then maintains output from said tube many times the rated output thereof until said stored energy is substantially reduced and means for coupling the oscillatory circuit to an antenna.

4. An oscillation generator, comprising a vacuum tube having a cathode, a grid and an anode, oscillatory circuits operatively associating said grid and said anode, means to bias said grid to prevent operation of said tube until the potential on said anode reaches a predetermined minimum value, a source of potential difference between said cathode and said anode, a high resistance in series between said source and said anode, and a capacitance of a value adequate to store a quantity of energy at said minimum potential sufficient, when radiated as a pulse, to produce a substantially powerful signal, said capacitance being connected in parallel with said source and said resistance, whereby said capacitance is slowly charged through said resistance until a value of potential approaching but less than said minimum value is reached, means to apply additional potential to increase the total applied potential to a value at least equal to said minimum, whereby said tube is caused to pass current and the said stored energy is discharged through said tube and maintains output from said tube many times the rated output thereof until said stored energy is substantially exhausted.

5. The method of radiating recurrent radio frequency pulses employing a charge storage device and an oscillation generator comprising the steps of operating the oscillation generator at a power level far in excess of the generator continuous service capacity and simultaneously rapidly interchanging charge between the oscillation generator and the charge storage device, radiating the generated oscillations, employing the resulting shift in potential on the charge storage device to terminate the operation of the oscillation generator, slowly restoring the initial charge on the charge storage device, and producing another cycle of operation.

6. The method of radiating recurrent radio frequency pulses employing an electron discharge device having a plurality of elements and a charge storage device connected between a pair of said elements, comprising the steps of generating oscillations at a power level far in excess of the generator continuous service capacity and rapid-

ly shifting the charge on said storage device, radiating the oscillations, employing the resulting shift in potential on the storage device to terminate conduction in the electron discharge device, and slowly restoring the initial charge on the charge storage device to initiate another cycle of operation.

7. The method of radiating recurrent radio frequency pulses employing a vacuum tube oscillation generator having charge storage means connected between the cathode and anode thereof comprising the steps of generating oscillations while rapidly decreasing the cathode anode potential by feeding cathode anode current into the charge storage device, radiating the oscillations, employing the resulting cathode anode potential drop to cause termination of oscillations, and gradually restoring the initial charge on the charge storage device to raise the cathode anode potential to institute a succeeding cycle of operation.

8. The method of radiating recurrent radio frequency pulses employing a vacuum tube oscillation generator comprising the steps of applying a voltage to the generator far in excess of its continuous service capacity to cause operation thereof, radiating the resulting oscillations, simultaneously feeding tube current to charge storage means to rapidly block the generator, and slowly restoring the initial charge on the charge storage means for initiation of a succeeding cycle of operation.

9. The method of radiating recurrent radio frequency pulses employing a charge storage device and an oscillation generator comprising the steps of slowly accumulating a charge in the charge storage device, rapidly discharging the charge through the oscillation generator at an input power level far in excess of its continuous service capacity, radiating the oscillations, and terminating oscillation for initiation of another cycle.

10. The method of radiating recurrent radio frequency pulses employing a charge storage device and an oscillation generator comprising the steps of slowly accumulating a charge in the charge storage device, rapidly discharging the charge through the oscillation generator at an input power level far in excess of its continuous service capacity, radiating the oscillations, and employing the resulting change in potential on the charge storage device to terminate operation of the generator for initiation of another cycle.

11. The method of radiating recurrent radio frequency pulses employing storage means for electrical energy and an oscillation generator comprising the steps of slowly accumulating energy in the storage means, rapidly discharging the energy through the oscillation generator at a rate far in excess of its continuous service capacity, radiating the oscillations, and terminating oscillations for initiation of another cycle.

12. The method of radiating recurrent radio frequency impulses employing storage means for electrical energy and an oscillation generator, comprising the steps of slowly accumulating energy in the storage means, rapidly discharging the energy through the oscillation generator at a rate far in excess of its continuous service capacity, radiating the oscillations, and employing the resulting change in potential on the storage means to terminate operation of the generator for initiation of another cycle.

13. A radio frequency pulse transmitter comprising a vacuum tube having cathode, anode, and control electrodes, circuit means intercon-

necting said electrodes to effect oscillation, means for coupling the circuit means to a radiator, means for applying an operating voltage to the tube far in excess of the tube's continuous service capacity, and means responsive to oscillations of the tube to rapidly bias an electrode thereof to cut off the tube.

14. A radio frequency pulse transmitter comprising an oscillation generator, and operating means therefore operative to feed power thereto at an input level far in excess of the continuous service capacity of the generator including blocking means operative responsive to the power delivered to the generator to hold the generator quiescent after an operating period for an interval effective to restrict the average input power to the generator's continuous service capacity.

15. A radio frequency pulse transmitter comprising an oscillation generator having means controlling operation thereof, power supply means operative to energize the generator at an input level far in excess of the generator's continuous service capacity, means operative on the control means responsive to operation of the generator to terminate operation thereof after a short period of operation, and time-delay control means operative to initiate operation of the generator after a quiescent interval many times as long as the operating period to restrict the average input power to the generator's continuous service capacity.

16. A radio frequency pulse transmitter comprising a vacuum tube having a plurality of electrodes, circuit means interconnecting the electrodes to effect oscillation, means for coupling the circuit means to a radiator, power supply means operative to feed power thereto at an input level far in excess of the continuous service capacity of the tube, charge storage means connecting the power supply to the tube to energize the same for pulse generation during charge of the condenser, and resistor means connected across the charge storage means to gradually discharge the same after generation of the pulse.

17. A radio frequency pulse transmitter comprising a vacuum tube having a plurality of electrodes, circuit means interconnecting the electrodes to effect oscillation, means for coupling the circuit means to a radiator, power supply means operative to feed power thereto at an input level far in excess of the continuous service capacity of the tube, charge storage means connected to an electrode operative to collect current received thereby and developed a potential thereon responsive to oscillation to terminate oscillation, and resistor means connected to the charge storage means to gradually restore the initial charge conditions of the charge storage means.

18. A radio frequency pulse transmitter comprising a vacuum tube having at least anode and cathode electrodes, circuit means connecting the electrodes to effect oscillation under the application of voltage, a radio frequency load circuit for coupling the circuit means to a radiator, power supply means furnishing an operating voltage operative to drive the tube at a power level far exceeding its continuous service capacity, charge storage means connected between the specified electrodes and operative on discharge through the tube at power supply voltage to generate a powerful radio frequency pulse, and impedance means connecting the power supply to the charge storage means operative to charge the same at

a limited rate to power supply potential when the tube is non-conductive and having an impedance value sufficient to substantially block current flow from the power supply means to the tube during discharge of the charge storage means, whereby the pulse is generated from energy stored in the charge storage means.

19. A radio frequency pulse transmitter comprising a vacuum tube having at least anode and cathode electrodes, circuit means connecting the electrodes to effect oscillation under the application of voltage, a radio frequency load circuit for coupling the circuit means to a radiator, power supply means furnishing an operating voltage operative to drive the tube at a power level far exceeding its continuous service capacity, means connecting one terminal of the power supply to one of the specified electrodes, charge storage means connected between the other terminal of the power supply to the other specified electrode whereby power is discharged through the tube into the charge storage means to charge the same and simultaneously generate a powerful output pulse in the load circuit, said pulse being terminated with charging of the charge storage means, and conductive impedance means connected across the charge storage means becoming operative after termination of pulse generation to discharge the charge storage means preliminary to the generation of the succeeding pulse.

20. A radio frequency pulse transmitter comprising a vacuum tube having at least anode and cathode electrodes, circuit means connecting the electrodes to effect oscillation under the application of voltage, a radio frequency load circuit for coupling the circuit means to a radiator, power supply means furnishing an operating voltage operative to drive the tube at a power level far exceeding its continuous service capacity, means connecting one terminal of the power supply to one of the specified electrodes, impedance means connecting the other terminal of the power supply to the other specified tube electrode, charge storage means connected to said other tube electrode and to one terminal of the power supply, whereby charge is interchanged between the tube and the charge storage means during oscillation to shift the said other electrode potential and terminate oscillation after a pulse generating period and the potential change on the charge storage means is slowly restored through the impedance means to restore operating potential for reinitiating oscillation.
